UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 10, 1924. Serial No. 725,169.

To all whom it may concern:

Be it known that I, HERBERT A. WALLACE, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type comprising train carried governing means controlled by energy received from the trackway. More particularly my invention relates to the trackway portion of such apparatus.

15 I will describe one form and arrangement of trackway apparatus embodying my invention, and will then point out the novel 20 features thereof in claims.

The accompanying drawing is a diagrammatic view showing one form of trackway apparatus embodying my invention.

25 Referring to this drawing, the reference characters 1 and 1^a designate the track rails of a railway over which traffic normally moves in the direction indicated by the arrow. These rails are divided by means of 30 insulated joints 2 into a plurality of successive track sections A—B, B—C, etc.

35 Each track section is provided with a track relay designated by the reference character R with an exponent corresponding to the location and comprising a winding 3 connected across the rails adjacent the entrance end of the corresponding section. Each of the relays R also comprises a winding 4 constantly supplied with alternating current. As here shown this alternating current is supplied to each relay from an associated line transformer designated by the reference character T with an exponent corresponding to the location and having its 40 secondary 12 constantly connected with winding 4 of the associated relay R. The primary 13 of each line transformer T is constantly supplied with alternating current from some suitable source such as an alternator M over line wires 14 and 14^a. It follows that each relay R is responsive to the relative polarity of the current supplied to winding 3.

45 A track transformer designated by the

reference character J with an appropriate exponent is provided for each section and has its secondary winding 8 constantly connected across the rails adjacent the exit end of the corresponding section. An impedance 7 is interposed, as usual, between the secondary 8 of each track transformer J 50 and one rail 1 of the corresponding section. Associated with each track relay R is a repeater relay designated by the reference character G with a suitable exponent. Each relay G may be the usual and well known 55 "bridging relay" customarily used in 3-indication light signals to prevent the display of a stop indication as the indication changes from proceed to caution or vice versa. Referring particularly to relay G^B, the circuit for this relay may be traced from secondary 12 of transformer T^B, through wires 15, 27, 45 and 33, contact 34 of track relay R^B in either extreme position, wires 35 and 36, winding of relay G^B, and wires 37, 21 and 22 60 back to secondary 12 of transformer T^B. It will be clear that this circuit is closed, and therefore that relay G^B is energized, whenever track relay R^B is energized in either 65 direction, but that the circuit is open when relay R^B is de-energized. When relay G^B is energized, current flows from secondary 12 of transformer T^B, through wires 15, 27, 45 and 33, front contact 28 of relay G^B, 70 primary 9 of transformer J^B, front contact 29 of relay G^B, and wires 31 and 22 back to transformer T^B. When this circuit is closed, 75 section A—B is supplied with track circuit current of one relative polarity which I will hereinafter term "normal" relative 80 polarity and track relay R^A is then energized in such direction that its contact fingers are swung to the right. When relay G^B is de-energized the circuit for transformer J^B may be traced from secondary 12 of transformer T^B, through wires 15, 27 and 32, 85 back contact 29 of relay G^B, primary 9 of transformer J^B, back contact 28 of relay G^B, and wires 31 and 22 back to transformer T^B. When this circuit is closed section A—B is 90 supplied with track circuit current of the other relative polarity, which I will herein- 95 after term "reverse" relative polarity, and track relay R^A is then energized in such 100 manner that its contact fingers are swung to the left. It will be seen, therefore, that 105

the contacts 28 and 29 of each relay G constitutes a pole-changer for controlling the relative polarity of the track circuit current for the section next in rear.

- 5 Means are also provided for supplying the rails of each section in parallel with a current which I will hereinafter term a "loop" current. For this purpose I connect an impedance 5 across the rails adjacent the entrance end of each section and a similar impedance 6 across the rails adjacent the exit end of each section, and the connections of the loop circuits are made to the mid-points of these impedances. The immediate source 10 of loop current for each track section is a loop transformer designated by the reference character P with an exponent corresponding to the location. Referring particularly to transformer P^B , this transformer 15 is supplied with current when relay R^B is energized in either direction and relay G^B is also energized, by virtue of a circuit which passes from secondary 12 of transformer T^B , through wires 15, 27, 45 and 33, 20 contact 34 of relay R^B in normal or reverse position, wires 35 and 38, front contact 39 of relay G^B , wire 40, primary 11 of transformer P^B and back to secondary 12 of transformer T^B . Transformer P^B is provided with a secondary 10 having its middle point 10^a constantly connected, by means of wire 41, with impedance 5 in section A—B. When relay R^B is energized in the normal direction the left hand end of secondary 10 25 is connected with impedance 6 in section A—B by wire 44 and normal contact 42 of relay R^B , and when relay R^B is energized in the reverse direction the right hand end of secondary 10 is connected by means of 30 wire 43 and reverse contact 42 of relay R^B with impedance 6. When relay G^B is energized, section A—B is supplied with loop current of normal relative polarity or reverse relative polarity according as relay R^B is energized in the normal direction or 35 the reverse direction.

Each track section is further provided with a trackway signal of any suitable form. As here shown the signals are 3-indication 40 light signals, each designated by a reference character S with an exponent corresponding to the location and each comprising a stop unit 47, a caution unit 48, and a proceed unit 49, arranged to give distinctive indication, as by projecting beams of differently colored light. Referring particularly to signal S^B , this signal is provided with a proceed circuit which may be traced from secondary 12 of transformer T^B 45 through wires 15 and 16, front contact 17 of relay G^B , wire 18, contact 24 of relay R^B in normal position, wire 26, proceed unit 49 of signal S^B , and wires 19, 20, 21 and 22, back to secondary 12 of transformer T^B . 50 This circuit is closed only when relay R^B is

energized in the normal direction and relay G^B is also energized, under which conditions signal S^B displays a proceed indication. When relay R^B is energized in the reverse direction, and relay G^B is also energized, current flows from secondary 12 of transformer T^B , through wires 15 and 16, front contact 17 of relay G^B , wire 18, contact 24 of relay R^B in reverse position, wire 25, caution unit 48 of signal S^B and wires 19, 20, 21 and 22, back to secondary 12 of transformer T^B . When this circuit is closed, signal S^B displays a caution indication. When relay G^B is de-energized, as by de-energization of relay R^B , a stop circuit is 70 closed for signal S^B , over which current flows from secondary 12 of transformer T^B , through wires 15 and 16, back contact 17 of relay G^B , wire 23, stop unit 47 of signal S^B , and wires 19, 20, 21 and 22, back to transformer T^B . When this stop circuit is closed, signal S^B displays a stop indication. 75

Before explaining the operation of the apparatus as a whole, it should be pointed out that the trackway apparatus herein shown and described is suitable for co-operation with train carried governing means so that when the train occupies the stretch of track which is supplied with track circuit current and with loop current both of normal relative polarity, the train receives a proceed indication; when the stretch of track occupied by the train is supplied with track circuit current and with loop current the polarity of either of which is reversed with respect to the other, the train receives a caution indication; and when the train is on a stretch of track to which the supply of track circuit current or loop current is for any reason interrupted, a stop indication is received on the train. It will thus be plain that the indications received on the train are responsive, not only to the presence of track circuit current and loop current in the trackway, but also to the polarities of these currents with respect to each other. 90

As shown in the drawing, the section to the right of point C is occupied by a train indicated diagrammatically at V. Track relay R^C is therefore de-energized and repeater relay G^C is also de-energized. The circuit for primary 11 of transformer P^C is now open at back contact 39 of relay G^C and also at contact 34 of relay R^C . Section B—C therefore receives no loop current. Track circuit current of reverse relative polarity is, however, supplied to section B—C by transformer J^C , the supply of current to the primary of this transformer being reversed by contacts 28 and 29 of relay G^C . Back contact 17 of relay G^C being closed, signal S^C displays a stop indication. The track circuit current of reverse relative polarity supplied to section B—C energizes relay R^C in the reverse direction. Re- 100

lay G^B is therefore energized, thus supplying track circuit current of normal relative polarity to section A—B. Transformer P^B is supplied with alternating current, but reverse contact 42 of relay R^B is closed and therefore the loop current supplied to section A—B by secondary 10 of transformer P^B is of reverse relative polarity. The caution circuit for signal S^B is now closed at reverse contact 24 of relay R^B , and front contact 17 of relay G^B , and signal S^B , therefore, indicates caution. Relay R^A is now energized in the normal direction, and relay G^A is of course energized. As a result, track circuit current of normal relative polarity is supplied to the section to the right of A, as explained in connection with section A—B. The closing of normal contact 42 of relay R^A also supplies loop current of normal relative polarity from secondary 10 of transformer P^A to the section to the left of A, and the closing of contact 24 of relay R^A and front contact of relay G^A , completes the proceed circuit for signal S^A , which now indicates proceed.

If, under these conditions, a second train proceeds along the stretch of track shown in the drawing, such train will receive track circuit current of normal relative polarity and loop current of normal relative polarity as far as point A, and therefore will receive a proceed indication through the territory to the left of point A. As the train enters section A—B the reversal of the loop current will cause the train to receive a caution indication which persists as far as point B. As the train proceeds through section B—C it is supplied with track circuit current of reverse relative polarity, but as hereinbefore explained, no loop current is being supplied to section B—C and the train therefore receives a stop indication as it proceeds through this section. This stop indication will persist if the train enters the section to the right of point C because track circuit current will be shunted away from such train by the wheels and axles of train V already occupying this section.

Although I have herein shown and described only one form of trackway apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a stretch of railway track divided into a plurality of consecutive sections, a track circuit for each section including a track relay, means for supplying each said track circuit with alternating current of one relative polarity or the other according as the track relay for the section

next in advance is energized or de-energized, and means for supplying at least one rail of each section with loop current of one relative polarity or the other according as the track relay for the section next in advance is energized in the normal or the reverse direction. 70

2. In combination, a stretch of railway track comprising a plurality of successive sections, a track relay for each section responsive to the relative polarity of the track circuit current supplied to such section, a repeater relay for each section arranged to be energized when the associated track relay is energized in either direction, means for supplying each section with track circuit current of one relative polarity or the other according as the repeater relay for the section next in advance is energized or de-energized, and means for supplying at least one rail of each section with loop current of one relative polarity or the other according as the track relay for the section next in advance is energized in one direction or the other. 80

3. In combination, a forward and a rear section of railway track, a track relay connected across the rails of the forward section and responsive to the relative polarity of the current supplied thereto, means for supplying at least one rail of said rear section with loop current of one relative polarity or the other according as the track relay for the forward section is energized in one direction or the other, and means for supplying said rear section with track circuit current of one relative polarity when the track relay for said forward section is energized and of the other relative polarity when the last mentioned track relay is de-energized. 95

4. In combination, a stretch of railway track comprising a plurality of successive sections, a track transformer for each section having a secondary winding connected across the rails of the section, a track relay for each section connected across the rails of the section and arranged to be energized in a normal or a reverse direction according to the relative polarity of the current supplied thereto, a repeater relay associated with each track relay and arranged to be energized when such track relay is energized in either direction, said repeater relay comprising pole-changing contacts, a circuit for the primary of each track transformer including a source of alternating current and the pole-changing contacts of the repeater relay for the next section in advance, and means for supplying each section with loop current of one relative polarity or the other according as the track relay for the section next in advance is energized in the normal or reverse direction. 110

5. In combination, a plurality of succes- 125

130

4
sive sections of railway track, a trackway signal for each section so controlled that when the corresponding section is occupied the signal indicates stop, the signal next in rear indicates caution, and the second signal in rear indicates proceed; means for each section for supplying the rails of such section with track circuit current and with loop current the polarities of which currents are normal with respect to each other when the signal next in advance indicates proceed, for supplying the rails of the section with track circuit current and with loop current the polarity of which currents are reversed with respect to each other when the signal next in advance indicates caution, and for supplying the rails of the section with track circuit current but not with loop current when the signal next in advance indicates stop.

6. Railway traffic controlling apparatus comprising a stretch of railway track divided into a plurality of consecutive sections, a track circuit for each section including a track relay, means for supplying each said track circuit with alternating current of one relative polarity or the other according as the track relay for the section next in advance is energized or de-energized, and means for supplying at least one rail of each section with loop current of one relative polarity or the other according as the track relay for the section next in advance is energized in the normal or the reverse direction, but for interrupting the supply of loop current to each section when the track relay for the section next in advance is de-energized.

In testimony whereof I affix my signature,
HERBERT A. WALLACE.
